JOHN GRANT, OF LOS ANGELES, CALIFORNIA

CUTTER MOUNTING FOR REAMERS

Application filed April 21, 1928. Serial No. 271,660.

This invention has to do with reamers or underreamers of the type used for drilling wells, and the invention is particularly concerned with means and arrangements for mounting the reaming cutters on the body of a reamer.

The invention is applicable to various kinds and types of reamers and likewise to various kinds and types of cutters. Also it is applicable to plain reamers, as well as to expanding reamers or underreamers. All this will be understood from the nature of the invention which is made clear in the following description of an illustrative embodiment.

For the purposes of explaining the invention I show a reamer having expansively movable cutters; and again I choose, but merely for purposes of illustration, to show cutters which expand by swinging movements. Such illustration has been adopted in order to indicate the range of applicability of the invention and is not to be considered, except as expressly limited in the appended claims, as a limitation upon the invention.

With these understandings, and describing the invention as applied to a swinging cutter expansive reamer, it is to be noted that a characteristic feature of the cutter mounting lies in the fact that the cutters or cutter-carrying elements are placed or assembled in operative position upon the body by lateral movement and placement, rather than by longitudinal movement. In most, if not all, of the swinging cutter reamers of which I am aware, it has been common to place the cutters or cutter-carrying elements in the body by longitudinal insertion, involving some complications of assembly and disassembly. The matter of disassembling the reamer to take out the cutters, and subsequently reassembling, is of some importance because of the fact that the cutters must be renewed or sharpened frequently. My new mode of assembly provides a comparatively simple operation, one that does not require the removal and replacement of a number of different parts, and furthermore provides such a structure that the body of the underreamer may be made essentially in one piece.

Proceeding to a detailed description of illustrative and typical forms of the invention applied to a particular type of cutter, I refer to the accompanying drawings in which

Figure 1 is a longitudinal central section of an expansive reamer in accordance with my invention.

Figures 2, 3 and 4 are cross sections, respectively, on lines 2—2, 3—3 and 4—4 of Figure 1.

Figure 5 is a longitudinal central section of another structural form.

Figure 6 is a cross section similar to Figure 2 but showing a modified construction.

Figure 7 is a longitudinal section similar to Figures 1 and 5 showing a further modification.

Figure 8 is a cross section on line 8—8 of Figure 7.

Figure 9 is a fragmentary side elevation of the form shown in Figure 7.

In the drawings the body of the reamer is shown at 10. This body may be generally cylindric in form with a taper-threaded pin 11 at its upper end for connection with the usual rotary drilling string 12, and with a taper-threaded box 13 at its lower end for connection with a drilling bit 15, or with a sub 16 which connects with the drilling bit. The body has the usual watercourse 17 to pass circulation water to the drilling bit.

In the particular form of reamer here illustrated the body may be provided with a plurality of cutter-receiving recesses 18 of any suitable number, depending upon the number of cutters used. I prefer here to show three cutters and three recesses. The recesses 18, or the recessed part of the body, may be of any specific formation that may be desired, depending upon the form of the cutters and upon their manner of movement. I here show swinging cutters and show the recesses 18 suitable to receive them. The body parts 20 and 21 above and below the recessed parts may be regarded as upper and lower heads; and either in both of these heads, as shown in Figure 5, or in one of them, as shown in Figure 1, I form suitable grooves or recesses to take and hold the end

or ends of the cutter carriers; then provide for holding the cutter carriers in place with a surrounding ring or rings, as will presently be described. These carrier receiving grooves will, of course, be formed to suit the formation of the particular type of cutter or cutter-carrier; and thus, for instance, to receive and support a swinging cutter-carrier the grooves may be so constructed that they 10 form bearings in which the carriers may swing. Thus, to proceed with the specific description of the formations shown in the drawings, in Figure 1 I show the upper head 20 provided with three vertically extending grooves or slots 25, the bottoms of these grooves or slots being semi-cylindric in form in order to form a good bearing surface for the pivot pins 26 of the cutter carriers 27. In the particular form here illustrated the 20 cutter carriers 27 are formed with a head 28 which swings upon the axis of pivot pin 26, and a roller axis pin 29 mounted at its upper end in head 28. The ultimate cutting element is here formed by a roller 30 rotatably mounted upon the pin 29. The lower end of roller pin 26 is set in a bearing block 27a which may, if desired, be made as a removable and renewable piece separate from the body and may be formed of any suitable or 30 selected material. These bearing blocks 27a may be insertable in the body and held in the body in the manner which will be readily understood from a consideration of Figures 1 and 4; and the lower end of pins 26 will 35 preferably fit in the bores of blocks 27a so that the pins may gyrate in the bore when the upper end of the pins swing with the heads 28. The heads 28 may either be mounted solidly on the upper pivot pin 26 or 40 the pivot pin 26 may be stationary and head 28 swing about the pivot pin. It may be preferable to make the pivot pin 26 swing with the head as thereby a better and longer bearing surface may be obtained for the 45 swinging movement; but whether or not that is the case, it will be seen that the construction affords a good and strong bearing for the pivot pin 26. In structures such as here described I do not subject the pivot pin to the 50 full forces and thrusts incident to reaming, rather supporting the head 28 directly on the body when the cutters are expanded; but such provisions are not a part of the present invention and need not be described.

55 It will be understood that the particular make-up of the cutters may be varied. I show them here as made up of the carriers (heads 28, 28a, pins 29, and pivots 26) and of the preferred ultimate cutting element (rollers 30); 60 but they can be otherwise formed. It will be understood that in the term "cutter" I mean to include the carrier and the ultimate cutting element.

To hold the pivot pins 26 in place a single surrounding ring 35 is screw-threaded at

36 onto the body and its sleeve-like lower portion 35a covers the open outer ends of slot 25 and confines the pivot pins 26. Preferably the construction is such that the sleeve 35a will confine the pivot pins closely in proper position and without any appreciable or large amount of loose play so that the pivot pins are preferably held back upon the semi-cylindric bearing faces of the slots. The sub or drill stem 12 may overhang the upper end 70 of sleeve 35 to prevent accidental loosening, as shown in the drawings.

In order to disassemble the type shown in Figure 1, it is only necessary to unscrew and elevate the sleeve 35a, when the upper ends 75 of the carriers can be moved directly outwardly and out of the slots 25, this outward swinging of the upper ends of the cutter-carriers being allowed by the fact that the lower ends of pins 26 fit loosely in the bores of bearing blocks 27a so as to allow such oscillation. Then the cutter carriers can be removed from bearing blocks 27a by a short 80 upward movement.

On the other hand in Figure 5 I have shown 90 a further application of the invention wherein the cutter carriers have lower swinging heads 28a similar to the upper heads 28; and lower pivot pins 26a are provided like the 95 upper pins 26. These lower pins 26a fit into body slots 25a which are the same as body slots 25; and these lower pins are likewise held in position by a sleeve ring 35b which is screw-threaded on the body and is overhung by the sub 16 to prevent its accidental unscrewing. In the form of Figure 5, when the 100 two rings 35a and 35b are unscrewed and moved longitudinally the cutter-carriers can be then removed from the body by direct outward movement.

The cutter-carriers here described may be broadly regarded as typical of any type of cutter-carrier, expansive or non-expansive. And such a cutter carrier may carry any type of ultimate cutting element, even though the 110 ultimate cutting element is in substance nothing more than a sharp edge formed upon the cutter-carrier itself. Likewise, if the cutter-carrier moves to expand, it may, in a broad conception of my invention, have any type 115 of expanding movement, the swinging movement being here illustrated and described in a broad sense as typical and only specifically to show the adaptation of my mounting means to a swinging cutter carrier and to 120 show that the mounting means may not only provide a mount but may also provide bearing surfaces for swinging movement.

The forms so far described have embodied 125 a body surrounding ring as the element for holding the pivot pins 26 inwardly. In the form shown in Figures 7, 8 and 9 the body is provided with the same slots as before, but the holding means becomes, for each pivot pin, a dove-tailed key or wedge 35c which 130

bears back against the pivot pin 26 or 26a. This key or wedge may preferably be dovetailed in section as is shown in Figure 8 and also wedge shaped as shown in Figure 9; so that when inserted from above it may be pressed or lightly driven tightly into place and will have no tendency to move out of its proper position. And these keys or wedges are then prevented from backing out by substantially the same arrangement as shown in Figures 1 and 5; but in Figure 7 I show a ring or washer 40 interposed between the drill stem element 12, or the sub 16, and the ends of the keys 35c, thus to show that the retaining means, 35 or 35a, need not directly engage the drill stem elements in order to be held in place thereby.

Also in Figures 7 and 9 I show the pivot pins 26 mounted in bearing slots contained in removable bearing blocks 41. For all functional purposes the bearing blocks 41 may be considered as a part of the reamer body. It will merely provide for easy renewal of the bearing faces if they should become worn. Figure 6 shows a similar application of the bearing blocks 41 to the form of device shown in Figures 1 or 5.

The foregoing indicates the scope of the invention by indicating various modifications, but other modifications of form and of adaptability of the invention will occur to those skilled in the art, and such are contemplated to be in the broad scope of the invention.

25 I claim:

1. In a reamer, the combination of a body having a groove adapted to receive a cutter carrier, a cutter with a part lying in the groove, a member mounted on the body to close the groove outside of the cutter and thus hold the cutter in place, said member being removable in a longitudinal direction from groove closing position on the body, and an element screw-threadedly joined to the end of the body and obstructing longitudinal removal of the groove closing member.

2. In a reamer, the combination of a body having a groove adapted to receive a cutter carrier, a cutter with a part lying in the groove, a member mounted on the body to close the groove outside of the cutter and thus hold the cutter in place, said member being removable in a longitudinal direction from groove closing position on the body, and a drilling-stem element screw-threadedly joined to the end of the body and overhanging the groove closing member to prevent its longitudinal withdrawal.

3. In a reamer, the combination of a body having a groove which opens laterally to a side surface of the body, the back surface of the groove being substantially semi-cylindric to form a bearing surface, a cutter with a pivot pin fitting in the groove and removable

therefrom by lateral outward movement away from the body, and a ring removably surrounding the body and overlying the groove to prevent lateral removal of the pivot pin.

4. In a reamer, the combination of a body having a groove which opens laterally to a side surface of the body, the back surface of the groove being substantially semi-cylindric to form a bearing surface, a cutter with a pivot pin fitting in the groove and removable therefrom by lateral outward movement away from the body, a member closing the groove opening outside the pivot pin to hold the pin normally in place, and removable from groove closing position on the body in a longitudinal direction and an element screw-threadedly joined to the end of the body and obstructing longitudinal removal of the groove closing member.

5. In a reamer, the combination of a body having a groove which opens laterally to a side surface of the body, the back surface of the groove being substantially semi-cylindric to form a bearing surface, a cutter with a pivot pin fitting in the groove and removable therefrom by lateral outward movement away from the body, a ring surrounding the body and overlying the groove to prevent lateral removal of the pivot pin, and removable from groove closing position on the body in a longitudinal direction and a drilling stem element screw-threadedly joined to the end of the body and overhanging the groove closing member to prevent its longitudinal withdrawal.

6. In a reamer, the combination of a body having a groove extending longitudinally of the body and opening out laterally to a side surface of the body, a longitudinal pivot pin in the groove and removable therefrom by lateral outward movement away from the body, a cutter mounted on the pivot pin and adapted to swing about its longitudinal axis, a member closing the groove opening outside the pivot pin to hold the pin normally in place and removable in a longitudinal direction from groove closing position, and an element screw-threadedly joined to the end of the body and obstructing longitudinal removal of the groove closing member.

7. In a reamer, the combination of a body having two spaced heads with an intervening cutter receiving recessed portion, a cutter having pivot pins at each end, said pivot pins being mounted in the body heads and forming the axes about which the cutter swings, at least one of said heads having a pivot receiving groove which extends longitudinally of the head and opens out laterally to a side surface of the head, a member closing the groove opening outside the pivot pin to hold the pin normally in place and removable in a longitudinal direction from groove closing position, and an element screw-

threadedly joined to the end of the body and obstructing longitudinal removal of the groove closing member.

8. In a reamer, the combination of a body having two spaced heads with an intervening cutter receiving recessed portion, a cutter having pivot pins at each end, said pivot pins being mounted in the body heads and forming the axes about which the cutter swings, both heads having pivot receiving grooves which extend longitudinally of the heads and open out laterally to side surfaces thereof, members closing said groove openings outside the pivot pins to hold the pins normally in place and removable in a longitudinal direction from groove closing position, and two drilling stem elements screw-threadedly joined to the opposite ends of the body and overhanging the groove closing members to prevent their longitudinal removal.

9. In a reamer, the combination of a body having a groove opening out laterally to a side surface of the body, a bearing insert carried in said body groove and removable therefrom by lateral outward movement away from the body, said insert having a pin-receiving recess, a cutter and a cutter pivot pin, said pivot pin having bearing in the insert recess, and a member mounted on the body closing the body groove and holding the bearing insert against lateral displacement in the body, said member being removable in a longitudinal direction from its groove closing position.

35 10. In a reamer, the combination of a body having a groove opening out laterally to a side surface of the body, a bearing insert carried in said body groove and removable therefrom by lateral outward movement away from the body, said insert having a pin-receiving recess, a cutter and a cutter pivot pin, said pivot pin having bearing in the insert recess, and a sleeve mounted around the grooved portion of the body, closing the body groove and holding the bearing insert against lateral displacement in the body, said sleeve being removable in a longitudinal direction from its groove closing position.

In testimony whereof I have hereunto set
50 my hand.

JOHN GRANT.
